UNITED STATES PATENT OFFICE.

CHARLES JOHNSON AND ARTHUR B. JOHNSON, OF MINNEAPOLIS, MINNESOTA.

LUMBER-CUT-OFF MACHINE.

Application filed November 22, 1922. Serial No. 602,653.

To all whom it may concern:

Be it known that we, CHARLES JOHNSON and ARTHUR B. JOHNSON, citizens of the United States, residing at Minneapolis, in ⁵ the county of Hennepin and State of Minnesota, have invented certain new and useful Improvements in Lumber-Cut-Off Machines; and we do hereby declare the following to be a full, clear, and exact description of ¹⁰ the invention, such as will enable others skilled in the art to which it appertains to make and use the same.

Our invention relates to what is generally known to the trade as a "lumber cut-off machine". Machines of this character are extensively used in box factories and wood-working mills, generally, for cutting long boards into short sections of certain but different lengths. The invention is directed ²⁰ to certain improvements in the machine whereby highly improved results are obtained and, generally stated, the invention consists of the novel devices and combinations of devices hereinafter described and ²⁵ defined in the claims.

In lumber cut-off machines, it is the common practice to mount the saw on an oscillatory support for movements to and from cutting position, but in my present machine, I employ a plurality of saws and eccentrically mount the same on a rotating support so that the saws will be brought into sawing position in succession. In carrying out this radical departure in machines ³⁰ of the above character, I provide numerous and highly important novel devices and arrangements whereby the machine is not only made simple but of the very highest efficiency and will meet all of the conditions required for the general purposes ³⁵ above indicated.

In the accompanying drawings, which illustrate the invention, like characters indicate like parts throughout the several views.

Referring to the drawings:

Fig. 1 is a perspective showing the complete machine, except that the saw guard has been removed to better illustrate the arrangement of the saws;

Fig. 2 is a vertical section taken from front to rear centrally through the machine approximately on the line 2—2 of Fig. 3;

Fig. 3 is a horizontal section taken on the line 3—3 of Fig. 2, some parts being ⁵⁵ shown in full; and

Fig. 4 is a vertical section taken on the line 4—4 of Fig. 2.

In the arrangement illustrated, all of the running parts of the machine, except the ⁶⁰ saws, are mounted within a housing or cabinet 5, the top plate of which and a horizontal extension 6 therefrom afford a feed table for the lumber to be cut off. The outstanding end of the table extension ⁶⁵ 6 is shown as supported by a post 7.

Secured to and extending along the table-forming top and extension 6 and projecting far beyond the former is a guide rail ⁷⁰ 8, see Figs. 1 and 2 preferably angular in cross-section, the same being provided with a deep notch 9, just outward of the housing 5, to clear the saws presently to be noted. Mounted on the projecting portion of this guide rail 8 is a plurality of longitudinally spaced independently operative ⁷⁵ stop fingers or gauge devices 10, which, so far as this invention is concerned, may be operated in any suitable way to variably gauge the length of the board to be sawed ⁸⁰ off. Preferably, however, these stop fingers are of substantially the arrangement disclosed in application for Letters Patent of the United States Serial Number 549,669, ⁸⁵ executed by Charles Johnson and filed of date April 5, 1922, and entitled "Lumber cut-off machine."

Centrally secured to one side of the housing ⁹⁰ 5 and projecting within the interior thereof is a bearing bracket 11, and secured to the other side of said housing at the exterior thereof is an upstanding bearing bracket 12. Located within the housing is a revoluble yoke 13, which has oppositely projecting axial bearing sleeves 14 and ⁹⁵ 15 and also has diametrically projecting laterally spaced pairs of arms 13'. The long inner sleeve 14, at its projecting end, is journaled in the bracket 11, while the shorter outwardly projecting sleeve 15 is ¹⁰⁰ journaled in the upper end of the bearing bracket 12.

The circular saws 16, of which, as shown, there are two in diametrically opposite locations, are secured to saw spindles or shafts ¹⁰⁵ 17 that are journaled in the pairs of laterally

spaced diametrically opposite arms 13' of the rotatable yoke 13. Between the supporting arms 13', the saw spindles 17 are provided with spur pinions 18 that are preferably of the fibre type. The saws 16 are located in a common plane that is outward of the adjacent side of the housing 5 and that side of the housing is provided with a large circular opening that is substantially closed by a rotating disk 19 secured to the yoke 13 and through which the sleeve 15 and the saw spindles 17 are passed.

A primary driving shaft 20 is extended through the housing 5 and is axially journaled in the bearing sleeves 14 and 15 of the rotatable yoke. This shaft may be driven in any suitable way, as by an electric motor or pulley and belt connections from a power-driven line shaft. Within the yoke 13, this primary driving shaft 20 is provided with a large spur gear 21 that directly meshes with the saw pinions 18. Between the bracket 11 and adjacent side of the housing, the shaft 20 is provided with a pulley 22 preferably of the stepped cone type. A belt 23 runs over the pulley 22 and over a reversely stepped cone pulley 24 that is carried by a countershaft 25 journaled in suitable bearings on the sides of the housing 5. This countershaft 25 is provided with a spur pinion 26 that meshes with a spur gear 27 carried by a second countershaft 28 also journaled in suitable bearings on the sides of the housing 5.

The countershaft 28 carries a small sprocket wheel 29 that is aligned with a much larger sprocket wheel 30 loosely journaled on the bearing sleeve 14 of the rotating yoke. A sprocket chain 31 runs over the sprockets 29 and 30. The sprocket wheel 30 has a laterally projecting annular clutch flange 32 that cooperates with an expandable clutch ring 33, the hub 34 of which is keyed or otherwise rigidly secured to the yoke sleeve 14, (see particularly Figs. 3 and 4). The clutch ring 33 is under normal tension to contract, but may be expanded by a wedge bolt 35 attached to a small lever 36 that is fulcrumed on an edge 37 of the expandable clutch ring and is forked so that it embraces the exposed portion of the sleeve 14. This forked end of the clutch lever 36 is arranged to be pressed toward the observer in respect to Fig. 3 and toward the left in respect to Fig. 4, by a loose collar 38 mounted on the sleeve 14. As shown, a fibre washer 38' is interposed between the sleeve 38 and forked end of the lever 36.

The sleeve 38 has a peripheral groove that is engaged by studs on the arms of a shipper fork 39 that is carried by a rock shaft 40. The rock shaft 40 is mounted in one end of the housing 5 and in a bracket 41 secured on one side of said housing, (see particularly Fig. 3), and near one end is provided with

a crank arm 42, (see Figs. 3 and 4), that is connected to the upper end of a vertical trip rod 43, the lower end of which is connected to a depressible treadle or foot piece 44 secured to the lower rock shaft 45 mounted in bearings on the sides of the housing, (see particularly Figs. 2 and 4). In the arrangement illustrated, the lower portion of the rod 43 is round and mounted to slide through a guide block 46 secured to a transverse bar 47 of the housing. A coiled spring 48 surrounds the round portion of said rod and is compressed between the guide block 46 and a nut 49 on said rod. This spring exerts an upward force which normally holds the treadle 44 raised and, operating through the arm 42, rock shaft 40 and fork 39, releases the clutch member 33 from the clutch member 32, so that the sprocket 30 will be free to rotate without imparting rotary motion to the yoke 13, which latter has been fully described and constitutes the saw carrier.

The free ends of the arms of the fork 39 are provided with lock lugs 50, which, in the normal position of the fork just above noted, are engageable with lock notches or detents 51, (see Fig. 2), formed in an annular flange 52 on one side of the revolute yoke 13. When the lugs 50 are engaged with the notches 51, the saw-carrying yoke 13 will be locked against rotation and held with the saws in an intermediate and inoperative position, that is, with the saws entirely below the work table or feed deck or, at any rate, out of the line of movement of the boards on said feed table or deck.

When the machine is in action, the saws rotate on their own axes while they are being revolved around the axis of the primary driving shaft 20 and of the yoke 13, and to protect the operator from the action of these saws, we provide a saw guard, which is secured to the adjacent side of the housing 5 and, preferably, comprises an annular trough-like casting 53 formed with tangential sawdust discharge spouts 54 and 55. The top portion of said trough is preferably formed with a displaceable section 56 hinged at 57 and normally gravity-held at its operative position shown in Fig. 2, in which position the boards may be freely fed under the same and into engagement with one or the other of the stop fingers 10, according to which the latter is moved into or across the plane in which the board is being moved.

For holding the treadle 44 depressed so that the saws will continue in action, we provide a lock lever 58 shown as pivoted at 59 to the saw guard 53 and arranged to be held where set by a ratchet bar 60 on said guard. When the lower end of the lever 58 is moved over the treadle 44, the latter will be held depressed and the fork 39 will be moved so as to release its lock lugs from the lock

notches 51 and operating on the lever 36 to set the clutch and cause the saws to begin their orbital travel.

5 *Operation.*

The operation of the various parts of the machine is probably clear from the foregoing description, but the complete operation may be summarized as follows:

- 10 As just above indicated, the orbital travel of the saws may be started by stepping on the treadle 44. If it is desired that the saws continue such orbital travel, the treadle 44 may be locked down, but if it is desired that 15 the saws make but one-half revolution, the clutch will simply be momentarily depressed, thereby causing the lock lugs 50 to be withdrawn from the lock notches 51, and this releases the saw-carrying yoke 13 and, moreover, sets the clutch 32—33 so that the gear 20 will become operative to transmit rotary motion to said yoke 13. If the treadle is quite quickly released, the lugs 50 will ride on the exposed edge of the cam flange 52 and 25 will hold the clutch 32—33 set until the saw-carrying yoke 13 has made one-half rotation and has carried one of the saws bodily through one-half of its orbital movement and past the position in which it cuts off the 30 board. At the completion of the said half-rotation of the yoke 13, the spring 48, acting through the connections described, will move the fork 39 and re-engage the lugs 50 with the notches 51, thereby stopping and locking 35 the yoke 13 against further rotation until the treadle is again depressed. When the lugs 50 are thus re-engaged with the notches 51, the clutch 32—33 will be automatically released, thereby disconnecting the saws 40 from their power-driving connections. As stated, if the treadle 44 be held depressed by the lever 54, the saws will be continuously rotated on their own axes and caused to continue their orbital travel or revolutions. 45 This continuous action is very desirable when rapid work is desired and it is made possible by the fact that there will be sufficient time intervening between the movements of the two saws to and past sawing 50 positions to enable the boards to be endwise adjusted against the depressed stop finger 10 and properly positioned for sawing.

With the driving connections described, the saws will, of course, be revolved on 55 their own axes at very high speed as compared with the speed at which they are revolved by the rotary yoke or saw carrier 13.

Sawdust thrown by the saws into the 60 saw guard will be ejected out through the tangential spouts 54 and 55 and, in practice, these spouts will frequently be connected to suction spouts leading to a fan or blower.

65 The opening in the side of the casing 5,

that is normally closed by the disk 19, is large enough to permit the yoke 13 and gear 30 to be passed therethrough. Preferably, said plate is made in two semi-circular sections rigidly secured to and rotatable 70 with the sleeve 15 of the saw-carrying yoke.

By the novel arrangement described, the saws are driven through a system of sun and planetary gears, which obviates the use of belts as a drive between the axial spindle 75 or shaft and the eccentrically mounted saws. When the disk 19 is in place, it keeps sawdust and the like from getting into the casing and the mechanism therein contained. It is necessary for the said disk to rotate 80 so that the saw spindles 17, which are passed therethrough, may be free to revolve around the axis of the carrying yoke. By the arrangement described, the gears are encased and protected within the casing, while the 85 saws are supported outside of the casing in position to perform their sawing function. In the preferred arrangement, the saws are diametrically offset in respect to the axis of the saw carrier or yoke, but the mechanism would be efficient for operating a 90 single eccentrically located saw.

What we claim is:

1. In a lumber cut-off machine, the combination with a supporting frame, of a 95 rotary saw-carrying yoke journaled in said frame, a driving shaft journaled concentrically to the axis of said yoke, a driving gear on said driving shaft located within said yoke, saw spindles eccentrically mounted on said yoke and equipped with circle 100 saws and having pinions meshing with said driving gear, said yoke having an axial sleeve and a power driven wheel one of which is loose, and means for connecting 105 the loose member, at will.

2. In a lumber cut-off machine, the combination with a supporting frame, of a 110 rotary saw-carrying yoke journaled in said frame, a driving shaft journaled concentrically to the axis of said yoke, a driving gear on said driving shaft located within said yoke, saw spindles eccentrically mounted on said yoke and equipped with circle 115 saws and having pinions meshing with said driving gear, said yoke having a long axial sleeve, a power-driven wheel normally loose on said sleeve, and a clutch for connecting said power-driven wheel to the sleeve on 120 said yoke.

3. The structure defined in claim 2 in further combination with means for locking said yoke with the saws in inoperative positions, when said clutch is released.

4. The combination with a rotary saw 125 carrier and a driving shaft journaled coincident with the axis thereof, of a circle saw eccentrically mounted on said saw carrier, connections for driving said saw from said driving shaft while it is being revolved by 130

said carrier, a driving wheel journaled around the axis of said saw carrier, means for rotating said driving wheel, a clutch for connecting said driving wheel to said yoke, and means for rotating said driving shaft.

5. The structure defined in claim 4 in further combination with means for locking said yoke against rotation when said clutch is released and said driving wheel is disconnected from said yoke.

6. The structure defined in claim 4 in further combination with yielding means tending to release said clutch.

7. The structure defined in claim 4 in further combination with means for locking 15 said yoke against rotation when said clutch is released and said driving wheel is disconnected from said yoke, and in further combination with yielding means tending to release said clutch and to lock said saw 20 carrier against rotation.

In testimony whereof we affix our signatures.

CHARLES JOHNSON.
ARTHUR B. JOHNSON.
